UNITED STATES PATENT OFFICE.

MORDUCH L. KAPLAN, OF BROOKLYN, NEW YORK, ASSIGNOR TO BEACON MINIATURE ELECTRIC CO. INC., OF NEW YORK, N. Y., A CORPORATION OF NEW YORK.

POCKET FLASH-LIGHT.

1,219,109.

Specification of Letters Patent. Patented Mar. 13, 1917.

Application filed January 16, 1915. Serial No. 2,514.

To all whom it may concern:

Be it known that I, MORDUCH L. KAPLAN, a citizen of the United States, and a resident of Brooklyn, in the county of Kings and State of New York, have invented certain new and useful Improvements in Pocket Flash-Lights, of which the following is a specification.

The invention pertains more particularly to flash lights adapted to be carried in the upper vest pocket without inconvenience and in the same manner that a fountain pen is carried.

The flash light of my invention is provided with a spring clip or member adapted, when the flash light is placed in the upper vest pocket, to embrace between itself and the side of the case of the article, the thickness of the material of the vest at the outer side of said pocket, the flash light being thereby held securely.

The present invention resides more particularly in the structure of the casing and in the electric circuit closer features. In the present instance a manually operative contact is rigid with the exterior casing and has a portion to be pressed inwardly through said casing for engaging a conductor connected with the battery, thereby to complete the circuit, and this conductor is preferably in the form of a sleeve closely fitting within but insulated from the exterior casing and in an electrical engagement with a spring which engages one end of the battery and is insulated from the exterior casing.

The rigid manually operative contact or switch is preferably formed of a spring clip which I utilize as the means for securing the flash light within the upper vest pocket, and the ball end of this spring clip when pressed inwardly through a hole in the side of the main casing against the interior conductor, will complete the circuit and the lamp will remain lighted so long as the spring clip is held inwardly. There are times, however, when a permanent light for a definite period is desired, as when a physician is, with the use of the light, examining the throat of a patient, and therefore in addition to the make and break manually operative switch formed from the spring clip, I provide a further or auxiliary circuit closer which is slidable and when in one position performs no necessary function and

when in its operative position completes the circuit and maintains the circuit closed with the lamp lighted so long as it is permitted to remain in such position. I preferably mount the slidable circuit closer on the 60 spring clip and provide on one end of the switch a projecting part which may pass through a hole in the exterior casing to engage the interior conductor when it is desired that the circuit shall be completed. 65

I preferably construct the barrel or exterior casing of the flash light to resemble in appearance a fountain pen, said casing being composed mainly of two parts secured together by bayonet joints.

The present invention embraces certain improvements on the flash light made the subject of Patent 1,182,965, May 16, 1916, to Bernard Benedict.

The invention will be fully understood 75 from the detailed description hereinafter presented, reference being had to the accompanying drawings, in which:

Figure 1 is a front elevation of a flash light embodying my invention;

Fig. 2 is a central vertical section on an enlarged scale, through the same, taken on the dotted line 2-2 of Fig. 1;

Fig. 3 is a detailed perspective view of an inner non-conducting lining for the interior of the handle end of the flash light, 85 said lining having two small apertures in one side thereof for the passage of the circuit closers;

Fig. 4 is a detailed perspective view of 90 a metal sleeve which in use fits within the lining shown in Fig. 3 when said lining is within the exterior shell or casing of the flash light;

Fig. 5 is a detached side elevation of the 95 handle section of the flash light, the circuit closer features being omitted;

Fig. 6 is a transverse section through the flash light on the dotted line 6-6 of Fig. 2;

Fig. 7 is a corresponding section through 100 the flash light taken on the dotted line 7-7 of Fig. 2, and

Fig. 8 is a side elevation of a portion of the handle section of the flash light showing the slidable circuit closer in operative 105 position and with the head portion thereof in section.

In the drawings 10 designates the exterior shell or casing of the flash light, and this shell or casing is of elongated form 110.

and meant to imitate, as far as convenient, the appearance of a fountain pen. The casing 10 will preferably be of metal and at one end carries a lamp 11 and reflector 12 therefor. The casing 10 is shown as made in two sections 13, 14 which with slight exception are the same in construction and mode of connection as the casing sections shown in the aforesaid patent of Bernard 10 Benedict. The reflector 12 is formed at its outer edge with a shoulder 15 to engage the outer edge of the casing section 13, and said reflector has a threaded neck 16 to receive the socket 17 of the lamp in a customary manner.

The lamp 11 is of usual character and has one terminal 18 in engagement, as usual, with one pole of the battery 19. The battery 19 will customarily be formed of two 20 cells in end to end relation and covered around their sides by paper or other non-conducting material, in the customary manner.

The handle section 14 of the main casing 25 is somewhat greater in diameter than the section 13, and said section 14 is lined by a sleeve 20 of non-conducting material, such as paper, and within the non-conducting sleeve 20 is a metal sleeve 21. The battery 30 19 has one end portion within the sleeve 21, and said portion of the battery at its end is pressed against by a coiled spring 22 which is a conductor and has one or more coils in electrical engagement with the sleeve 21. 35 The sleeve 21 is insulated from the metal casing section 14 by means of the sleeve 20, and also by means of a disk of paper or the like 23 fitted within the closed end of the section 14 and engaging the adjacent edges 40 of the sleeve 20. Within the outer end of the sleeve 21 is placed a second disk, which I number 24, of paper or the like, the disk 24 being in face to face contact with the disk 23 and receiving the outer end of the spring 45 22. It will be seen that the disks 23, 24 and the sleeve 20 insulate the contact sleeve 21 from the casing section 14, and that the circuit from the outer end of the battery 19 will be from the battery to the spring 22 and 50 thence to the sleeve 21. The non-conducting sleeve 20 is formed with two apertures or holes 25, 26, and these apertures are in line with corresponding apertures 27, 28 formed in the casing section 14 and expose at said apertures 27, 28 small portions of the conducting sleeve 21. The electrical connection of the outer casing of the flash light with the sleeve 21 to complete the circuit is made either at the apertures 27, 25 or at the apertures 28, 26, and in the present instance I utilize a spring clip 29 as one circuit closer, said clip being secured by rivets to the casing section 14 or otherwise suitably connected with said casing so as to be in electrical 65 engagement or connection therewith. On the outer end of the spring clip 29 is a ball or enlargement 30 adapted by the pressure of the thumb applied thereon to be moved, on the flexing of the spring 29, inwardly through the openings 27, 25 against the 70 sleeve 21, thereby to complete the circuit from the battery to the spring 22 and through the sleeve 21 to the spring clip or circuit closer 29 and thence to the casing section 14 which is in electrical engagement 75 with the casing section 13, reflector 12 and one terminal of the lamp, whose other terminal 18 is in electrical engagement with the forward end of the battery, as usual. The utilization of the spring clip 29 in connection with the openings 27, 25 and sleeve 21 is disclosed in the aforesaid Patent 1,182,965 and is not, therefore, specially claimed herein. In lighting the lamp with the spring clip or circuit closer 29, the ball 30 is pressed 80 inwardly against the sleeve 21 and the lamp remains lighted so long as pressure is maintained on said ball holding it against the sleeve 21. It is desirable in many instances that the circuit in a flash light should remain closed for a definite period and that the hand may be relieved from the duty of holding the closer or switch in operative position, and hence in accordance with my invention I provide an auxiliary circuit closer 90 95 or switch 31 which is preferably in the form of a strip of spring metal secured to a head 32, which I preferably mount on the circuit closer or spring clip 29, said head having a neck portion 33 extended through a guide 100 slot 34 in the circuit closer 29, and the closer or switch 31 being secured to the end of said neck behind the closer or spring clip 29. The switch or closer 31 is substantially concealed behind the spring clip or closer 29 105 and the head 32 connected therewith is in line with and slidable on the closer or clip 29, the movement of said head 32 from the position in which it is shown in Fig. 2 carrying the switch 31 from its inoperative position to its operative position illustrated in Fig. 8. The switch 31 is formed at its free end with an inward indentation or projection 35 which is adapted to the openings 28, 26 when said switch is in its operative position and to a recess 36 formed in the casing section 14 when said switch is in its inoperative position. When the switch 31 is in its inoperative position the projection 35 thereon rests within the recess 36 and against the 110 side of the non-conducting sleeve 20, and when by means of the head 32 the switch 31 is caused to slide to its operative position, the projection 35 thereof will move from said recess 36 into the openings 28, 26 and 115 engage the conducting sleeve 21, thereby completing the circuit and causing the lamp to light. After the switch 31 has been moved to its operative position the pressure of the thumb may be removed from the head 120 125 130

32, since said switch will remain in its operative position until manually retracted therefrom. A forward pressure of the thumb on the head 32 will move the switch 31 to its operative position and a reverse pressure of the thumb on said head will effect the retraction of the switch 31 to its inoperative position. The inner end of the projection 35 is rounded so that the same 10 may conveniently ride into and from the opening 26 in the sleeve 20.

The novel features of the present invention in comparison with the aforesaid Patent 1,182,965 reside in the circuit closer features hereinbefore described and particularly in the provision of the circuit closer 15 31 and parts coöperating therewith.

In the use of the flash light the circuit may be made by pressing the free end of 20 the resilient tongue or clip 29 inwardly through the openings 27, 25 and against the conductor 21 or the circuit may be closed by a forward pressure on the head 32 adapted to effect the sliding of the switch 31 from 25 its inoperative position, shown in Fig. 2, to its operative position, shown in Fig. 8. When the free end of the clip 29 is made use of for closing the circuit, the circuit will remain closed only during such period 30 as the pressure of the hand is exerted on the free end of said clip, but when the head 32 and switch 31 are made use of for closing the circuit, the circuit will remain closed so long as the switch is permitted to remain 35 in its operative position. In the use of either circuit closer the circuit is from the sleeve 21 to the clip 29 and thence to and through the exterior casing of the flash light, the switch 31 being in electrical connection with said clip.

What I claim as my invention and desire to secure by Letters Patent, is:

1. In a pocket electric light comprising an exterior casing having at one end a lamp 45 and containing a battery for the lamp, a clip for retaining the light in the pocket of the owner, and manually operative means for closing the circuit comprising an exposed slide and a circuit closer connected therewith, said slide being mounted on said clip and said casing having an opening 50 therein for said circuit closer when in its operative position.

2. In a pocket electric light comprising an exterior casing having at one end a lamp 55 and containing a battery for the lamp, a clip for retaining the light in the pocket of the owner, and manually operative means for closing the circuit comprising an exposed slide and a circuit closer connected therewith, said slide being mounted on said clip and requiring a forward movement to complete the circuit, whereby the material at the front of said pocket is permitted to prevent movement of said slide to circuit closing position while the light is in the 60 pocket.

3. In a pocket electric light comprising an exterior casing having at one end a lamp 70 and containing a battery for the lamp, means for retaining the light in the pocket of the owner and closing the circuit comprising a clip electrically connected with the casing and adapted when manually operated for that purpose to close the circuit, and further means for closing the circuit comprising an exposed slide and a circuit closer connected therewith, said slide being mounted on said clip and its said 75 closer being behind said clip.

4. In a pocket electric light comprising an exterior casing having at one end a lamp 80 and containing a battery for the lamp, means for retaining the light in the pocket of the owner and closing the circuit comprising a clip electrically connected with the casing and adapted when manually operated for that purpose to close the circuit, and further means for closing the circuit comprising an exposed slide and a circuit closer 85 connected therewith, said slide being mounted on said clip and its said closer being behind said clip, and said casing having an opening therein for said circuit closer when moved to its operative position 90 and also an opening for the free end of said clip when it is moved to circuit closing position.

Signed at New York city, in the county of New York and State of New York, this 100 13th day of January A. D. 1915.

MORDUCH L. KAPLAN.
